ELECTRICAL HEATING UNIT

Harry M. Parmley, Harrisburg, Pa.

Application December 20, 1945, Serial No. 636,221

5 Claims. (Cl. 219—41)

1

This invention relates to electrical heating units and particularly to that type of electrical heating unit adapted for use in the interior of liquid containers.

One object of the invention is to provide an electrical heating unit of this type which can be removably positioned within the liquid container, the unit being supported on the container closure in such fashion as to function with maximum efficiency.

Another object of the invention is to provide a heating unit of the type indicated which will be efficient in operation by reason of the provision of comparatively large upper and lower heat radiating surfaces.

A still further object of the invention is to provide an electrical heating unit supported by the closure for the container in which the unit is to be used, said unit being provided with breather means to permit the escape of air from the interior of the unit per se when the latter is in use.

With these and other objects in view, the invention consists in certain details of construction and combinations and arrangements of parts, all as will hereinafter be more fully described and the novel features thereof particularly pointed out in the appended claims.

In the accompanying drawing:

Figure 1 illustrates the unit positioned within one type of container, the view being essentially a sectional view taken longitudinally of the container and unit with a portion of the container closure being shown in elevation; and

Fig. 2 is a transverse sectional view on the line 2—2 of Fig. 1.

The present invention resides primarily in a heating unit adapted for use in heating liquids in containers of different types but in the present instance a container of the so-called thermos vessel type is illustrated, said vessel which is of the double wall type being indicated at 10. The vessel or container has an open upper end for filling and this opening is adapted to be closed with a closure 11 removably positioned therein. While the contents of the vessel may be discharged in various ways an outlet 12 is shown in the present instance, said outlet being threaded as at 13 for attachment of a faucet or other discharge control means (not shown).

Essentially, the present heating unit comprises an electrical resistance element with suitable lead connections supported on a member of electrical insulating material and a metal housing or casing for the electrical resistance element and its in-

2

sulating support, said housing and insulating support both being securely mounted in the closure 11 of the vessel so that the unit may readily be installed in and removed from the vessel merely by placing the closure in or removing it from the filling opening of the vessel. The housing or casing for the electrical resistance element comprises an upper tubular portion 14 whose upper end is secured in closure 11 by having its upper extremity turned down flush with the top surface of the closure as indicated at 15, a bead 16 being formed on the tubular member 14 immediately below the closure so as to prevent longitudinal displacement of the tubular member. At 10 its lower extremity the tubular member 14 merges into a cylindrical portion 14a which is essentially a continuation of portion 14 but which is of considerably greater diameter than the tubular portion 14 so that its upper and lower walls or surfaces constitute comparatively large heat radiating areas because, as will be later explained, the heat producing portion of the unit, i. e., the electrical resistance element is entirely housed within this cylindrical portion 14a of the unit casing.

25 Arranged concentrically within the tubular member 14 is an inner tubular member 17 of insulating material whose lower end is adapted to support a block or body of porcelain or other insulating material in which the electrical resistance element 18 is supported. The block of porcelain or other material has a hub portion 19 formed with a transverse rib 20 on its upper surface in which there are two slots for reception of binder posts 21, 22 to which the ends of the resistance element are connected and to which the lead wires 23 are also connected, said lead wires extending upwardly through the inner tubular insulating member 17 to a plug or socket 24 mounted in the upper end of that member. The hub portion 18 is also formed with an annular recess around its upper edge for reception of the lower end of the tubular member 17 and in order to take advantage of the comparatively large heat radiating surfaces formed by the upper and lower walls of the lower cylindrical portion 14a of the unit casing said block of porcelain is formed with a plurality of arms 25 radiating from the hub 18 and merging at their outer ends in an annular ring 26. In between said arms 25 the hub 18 is also formed with lugs 27 and the lugs and arms all have perforations formed therein through which the electrical resistance element can be threaded at points radially beyond the tubular members 14, 17. In other words, by having the lower cylindrical portion 14a of the casing of

greater cross sectional size than the tubular portion 14 and by mounting the resistance element in the arms and lugs of the porcelain block which may be described as being of spider formation the resistance element can be spread out over a comparatively large area to take advantage of the radiating capacity of the lower cylindrical portion 14^a of its casing.

In order to maintain the inner insulating member 17 and the porcelain band or ring 26 in proper spaced relation concentrically of the casing and to afford breather means to permit the escape of air when the unit is in use, spacer means in the form of strips or split rings of cork are interposed between those structural parts, as best illustrated in Fig. 1. For instance, a split ring or strip of cork 28 is positioned between the upper ends of the two tubular members 14 and 17 and strips or a split ring of cork 29 is interposed between the lower ends of those two tubular members while a third body of cork indicated at 30, which may also be either a split ring or strips, is interposed between the porcelain band 26 and the side wall of the lower cylindrical portion 14^a of the casing. Preferably these bodies of cork fit closely between the structural elements and maintain them in proper spaced relation at all times but, at the same time, air may escape through the split rings when current is passed through the electrical resistance unit which results in the air becoming heated and expanding.

The tube 17 may be of any desired insulating material and, of course, the casing composed of tube 14 and cylindrical portion 14^a may be of any suitable material although aluminum is preferred. Preferably the length of the two tubes 14, 17 and the depth or height of the cylindrical portion 14^a is such that the latter will be spaced an appreciable distance from the bottom of the container in order to take full advantage of the radiation of heat from the bottom of the portion 14^a. As stated, the vessel may be of any desired type and the discharge control means, therefore, may take various forms, neither of these elements actually forming any part of the present invention. Also, it is deemed unnecessary to illustrate any of the electrical connections as it will be understood that suitable means will be provided for attaching the heating unit when installed in the container to the usual house current. If desired an arrangement in the form of a steam whistle indicated more or less diagrammatically at 31 may be provided in the closure 11 to function as a signal when the liquid in the container has reached the boiling point so as to permit the heating unit to be disconnected and thus conserve current.

What is claimed is:

1. An electrical heating unit adapted to be removably positioned in a liquid container, said unit comprising spaced, concentric inner and outer tubular members mounted at their upper ends in a closure for said container, said inner member being formed of electrical insulating material and said outer member being of metal, spacer members having air passages therein interposed between said inner and outer members, an electrical heating unit supported at the lower end of the inner member, lead wires extending through the inner member from said resistance element to the upper end of the inner tubular member, and a cylindrical metal casing for said resistance unit mounted on the lower end of said outer member.

2. An electrical heating unit adapted to be removably positioned in a liquid container, said unit comprising spaced, concentric inner and outer tubular members mounted at their upper ends in a closure for said container, said inner member being formed of electrical insulating material and said outer member being of metal, spacer members having air passages therein interposed between said inner and outer members, an electrical heating unit supported at the lower end of the inner member, lead wires extending through the inner member from said resistance element to the upper end of the inner tubular member, and a cylindrical metal casing for said resistance unit mounted on the lower end of said outer member, said cylindrical casing extending radially beyond the outer tubular member to form upper and lower heat radiating surfaces.

3. An electrical heating unit adapted to be removably positioned in a liquid container, said unit comprising concentrically spaced inner and outer tubular members mounted at their upper ends in a closure for said container, said inner member being formed of electrical insulating material and said outer member of metal, a body of insulating material mounted in the lower end of the inner member, said body having radial arms merging at their outer ends into a continuous band, an electrical resistance unit supported in said arms at points radially beyond said tubular members, a cylindrical metal housing having upper, lower and side walls enclosing said band, said cylindrical housing forming a radially enlarged continuation of the outer tubular member and being concentrically spaced from said band, and split rings of cork interposed between said band and the side wall of the cylindrical housing and between said inner and outer tubular members.

4. An electrical heating unit adapted to be removably positioned in a liquid container, said unit comprising a tubular member of insulating material mounted at its upper end in a closure for said container, a porcelain body having a hub portion mounted in the lower end of said tubular member with arms extending radially from said hub and merging into a peripheral band, a metal housing mounted on said closure and enclosing said porcelain body and tubular member, an electrical resistance element supported in the arms of said porcelain body, lead wires connected to said resistance element and extending through said tubular member to the upper end of the latter, and split cork rings interposed between said band and housing and between said tubular member and band.

5. An electrical heating unit adapted to be removably positioned in a liquid container, said unit comprising a metal housing mounted at its upper end in a closure for said container and terminating at its lower end in a radially enlarged cylindrical portion, a tubular member of insulating material mounted at its upper end in said closure and extending downwardly within the housing to said enlarged cylindrical portion of the housing, a body of porcelain secured in the lower end of said tubular member and positioned in the cylindrical portion of the housing, said body consisting of a hub portion with radial arms merging into an annular band, an electrical resistance element supported in said arms, a rib on the upper surface of said hub, binding posts mounted in said rib and connected to said resistance element, lead wires attached to said binding posts and extending through said tubular

member to the upper end thereof, and split bands of porous material interposed between said tubular member and housing and between the cylindrical portion of the housing and the band of said porcelain body.
